UNITED STATES PATENT OFFICE.

PEDRO DONAIRE, OF HABANA, CUBA.

CONSTRUCTION FOR RAISING SUNKEN VESSELS.

1,390,097.

Specification of Letters Patent.

Patented Sept. 6, 1921.

Application filed September 11, 1920. Serial No. 409,590.

To all whom it may concern:

Be it known that I, PEDRO DONAIRE, a citizen of Cuba, residing at Habana, Cuba, have invented new and useful Improvements 5 in Construction for Raising Sunken Vessels, of which the following is a specification.

My invention has reference to a method and means for raising sunken marine vessels.

In carrying out my invention, I propose to attach to the sides of a sunken vessel, adjacent to the bow and stern thereof, heavy chains of a strength to raise and support 15 the vessel on the surface of the water, said chains being directed angularly over floats or pontoons that are secured in a novel manner to the sterns of wrecking tugs or similar vessels which are anchored at points diagonally with respect to the sunken vessel, the 20 said chains being further directed around windlasses on the said tugs, and simultaneous motion is imparted to said windlasses for drawing on the chain to raise the sunken vessel, the resistance offered by the sunken vessel being compensated for by the anchorage for the tugs.

It is also my purpose to produce a method and means for raising sunken vessels, in 30 which four wrecking tugs or similar vessels are arranged in spaced pairs diagonally with respect to each other and to the sunken vessel and anchored in such position, a float or pontoon, of a novel construction is attached 35 to the stern of each of the tugs and provided with means for guiding thereover a chain or cable that has one of its ends arranged around a drum or windlass in the respective tugs, and its other end attached (by a diver) 40 to the sides of the sunken vessel at the bow and at the stern thereof, the operating mechanism for winding the cables on the drums or windlasses being simultaneously actuated whereby the strain or pull will be exerted 45 on all of the chains or cables, and the buoyed elements at the sterns of the tugs preventing the sinking of the said tugs at the stern portions thereof, the anchors resisting the strain of the chains or cables at the bow end 50 of the tugs, with the result that the vessel will be sufficiently raised to permit of the pumping out thereof for repairs which will permit of the floating of the vessel.

I attain the foregoing objects, and others 55 which will appear as the nature of the in-

vention is better understood by a construction, combination and operative arrangement of parts illustrated in the drawings which accompany and form part of this application, or such modifications therefrom as fall 60 within the scope of the claims.

In the drawings:—

Figure 1 is a plan view illustrating the manner in which a sunken vessel is raised in accordance with this invention.

Fig. 2 is a side elevation of the stern portion of one of the wrecking tugs, part being in section, and illustrating the arrangement of the buoyant guide element for the chain or cable attached to the stern of a vessel, the 70 said last mentioned element being in section.

Fig. 3 is a perspective view of the buoyant element or pontoon.

In Fig. 1 of the drawings, a sunken vessel to be raised in accordance with this invention is indicated by the numeral 1. Attached to the sides of the vessel at the bow and stern thereof are strong chains or cables 2. These pairs of cables are directed at opposite angles away from the vessel 1, being disposed diagonally with respect to each other and to the said vessel.

Anchored from their bows in the body of water in which the vessel 1 is sunk are wrecking tugs 3. The tugs 3 are arranged 85 in a direct line with the respective chains 2, and each of the tugs or vessels 3, at the stern portion thereof has supported thereon a drum or windlass 4 to which the ends of the chains of the respective flexible elements are 90 connected and around which the said elements are designed to be wound. Suitable mechanism is employed for revolving the drums 4. As any desired mechanism may be employed for this purpose, an illustration 95 or a description thereof is not deemed necessary. It is necessary to state, however, that all of the drums are revolved simultaneously and at the same rate of speed.

Were the drums actuated to revolve the 100 cables, when the tugs 3 are anchored as above described, the weight of the vessel 1 would cause the sinking of the tugs at the stern portions thereof. To prevent this, I arrange on the stern of each of the tugs 3 105 a pontoon which has its body portion of a hollow preferably rectangular structure, and therefore presents the appearance of a pontoon. The pontoons are indicated by the numeral 5, and each of the said pontoons, at 110

one of its ends has a notched portion 6 which is shaped to receive therein the stern of the tug to which the pontoon is attached. On the upper face of each of the pontoons, inward, but to the sides of the notch 6 there are secured eye members 7 to which are attached links 8 that have their ends connected to eyes 9 that are secured to the sides at the stern portion of the respective tugs 3. Thus each of the pontoons 5 is both hingedly connected and held in contact with the stern of the respective tugs 3.

Each pontoon 5 has a central opening therethrough which is round in plan and 15 concaved in cross section and within each of these openings is received a hollow spherical buoyant member 10. The spherical member 10 fully closes the opening in the pontoon. The members 10 add to the buoyancy of the pontoons, being, of course, air tight. On the upper face of each of the spheres, at the center thereof there are spaced brackets 11 between the parallel arms of which are shafts 12 on which are journaled concave rollers 13 and around these rollers the flexible elements 2 are directed. The body of each of the pontoons 5 has an angle passage 14 therethrough, and through this passage is directed the flexible element 2. The passage 14 is surrounded by a wall.

As previously stated, all of the drums are designed to be revolved to wind the elements 2 therearound simultaneously and at the same rate of speed. Also, as previously 35 stated, the tugs 3 are anchored from their bows. The flexible elements 2 are secured to the sunken vessel 1 by divers. The turning of the drums, will, of course, draw on the flexible elements 2, and as the same are 40 wound around the drums, the vessel 1 will be raised. The direct strain exerted between the flexible elements 2 on the respective tugs 3 is resisted by the anchorage for the tugs. The downward strain which 45 would be otherwise exerted upon the stern ends of the tugs is delivered directly to the pontoons or buoyant members 5 so that danger of the tugs sinking at the stern end thereof will be thus effectively overcome. The elements 8 are detachable, so that the 50 pontoons or buoyant members 5 may be removed from the stern of the tugs and arranged on the decks thereof when not required for use, as when the tugs are turning 55 away or toward the wreck. The vessel 1 will be raised so that the deck thereof will be brought above or in a line with the body of water in which the said vessel has sunk, so that apparatus from a mother ship for the 60 tugs may be employed for pumping the said vessel 1 to permit of proper repairs being made therein so that the vessel can be floated, and when once floated the vessel can be towed by two or more of the tugs.

65 It is thought that the foregoing descrip-

tion, when taken in connection with the drawings will fully set forth the method and means employed for salving sunken vessels without further detail description, and therefore such will not be attempted. 70

Having thus described the invention, what I claim, is:—

1. In a means for raising sunken vessels, strong flexible elements secured to the sides at the bow and stern of a sunken vessel and 75 directed at outward angles therefrom, buoyant members anchored at the front thereof in a line with the respective flexible elements, drums carried by said members, to which the respective elements are attached, 80 means for simultaneously revolving the drums at the same rate of speed, and buoyant directing means for the elements hingedly connected to rear or stern portions of the respective buoyant members and having 85 one of their ends in contact with the said stern portions of said buoyant members.

2. In a means for raising sunken vessels, strong flexible elements secured by divers to the sides at the bow and stern of a sunken 90 vessel and directed at outward angles therefrom, tugs anchored from the bows thereof in a line with the respective flexible elements, drums on the tugs, means for revolving the drums simultaneously and at the 95 same rate of speed, and buoyant members, each having one of its ends loosely connected to and in contacting engagement with the sterns of the respective tugs, and guide means on the top adjacent to the outer end 100 of the buoyant members for guiding the cables thereover and through said buoyant members.

3. In a means for raising a sunken vessel, strong cables secured to the sides at the bow 105 and stern of a sunken vessel, and directed at outward angles therefrom, tugs anchored from their bows in a line with the respective cables, a drum on each of said tugs to which the respective cables are secured, means for revolving the drums simultaneously and at the same rate of speed, a pontoon having a notched edge engaging the stern of the respective tugs, means for loosely hinging the 110 pontoon to the respective tugs, and anti-frictional guides on the top of each pontoon, adjacent the outer end thereof for directing the cable through the outer end of the pontoon.

4. In a means for raising a sunken vessel, 115 strong cables secured to the sides of the bow and stern of a sunken vessel and directed at outward angles therefrom, tugs anchored from the bows thereof in a line with the respective flexible elements, drums on 120 said tugs to which the respective flexible elements are secured, means for simultaneously revolving the drums at the same rate of speed, a hollow pontoon at the stern of each of the tugs, each of said pontoons hav- 125

ing a notched end to receive the stern keel of the said tugs, removable means for hing-
edly connecting the pontoon to the respective tugs, a hollow globular member dis-
5 posed in the center of each of the pontoons and projecting above the top and bottom thereof, concaved anti-frictional guiding means for the cables said globular members on the sides and at the outer and upper sur-
10 face thereof, and said pontoons having each a passage therethrough adjacent to the outer end thereof for the passage of the respective cables.

5. In a means for raising a sunken vessel, strong flexible elements secured to the sides at the bow and stern of a sunken vessel and directed at outward angles therefrom, tugs anchored from the bows thereof in a line with the respective flexible elements, drums 15 thereon to which the said respective ele-

ments are attached, means for simultaneously revolving the drums, buoyant means at and in contact with the stern of the respective tugs each having a central portion which projects above the top and the bot- 25 tom thereof, guide means on the upper and outer surface of said portions serving as guides for directing the flexible elements through the outer ends of the respective pontoons, and said flexible elements, when 30 strain is exerted thereon designed to first exert a pushing action against the buoyant means and to hold the stern of the tug from sinking when the outer end of the pontoon is arranged at a slight downward angle 35 with respect to the tug and is partially immersed below the surface of the water incident to the strain of the cable thereon.

In testimony whereof I affix my signature.
PEDRO DONAIRE.
